UNITED STATES PATENT OFFICE.

JOHN E. HUBBELL, OF NEW YORK, N. Y., ASSIGNOR OF ONE-THIRD TO LOUIS WILPUTTE
AND TWO-THIRDS TO ALICE A. WILPUTTE, BOTH OF NEW ROCHELLE, NEW YORK.

DOOR-HANDLING MACHINE.

1,357,057.

Specification of Letters Patent. Patented Oct. 26, 1920.

Application filed April 20, 1920. Serial No. 375,279.

To all whom it may concern:

Be it known that I, JOHN E. HUBBELL, citizen of the United States, and resident of New York, in the county of New York and 5 State of New York, have invented certain new and useful Improvements in Door-Handling Machines, of which the following is a specification.

The general object of my present invention is to provide an improved door handling mechanism especially devised for moving plug doors into and out of the ends of the horizontal coking chambers of a by-product coke oven. These doors are quite 10 heavy, ordinarily weighing several tons each, and to remove such a door from its closed position it is necessary to lift the door slightly to take the weight of the door off the door sill, or bottom wall of the oven chamber, and then to move the door horizontally out of the coke chamber, after 15 which it is usually necessary to move the door transversely of the length of the oven chamber to get it out of line with the latter. Heretofore, it has been thought necessary to maintain a door of this type in parallelism with itself as it is being inserted in and removed from the end of the oven chamber. I have discovered, however, that 20 such a door may be readily opened by an initial rotation of the door about a horizontal axis adjacent and parallel to the bottom edge of the door. This rotative movement of the door carries the upper end of 25 the door part way out of the oven chamber and lifts the bottom edge of the door off the door sill, after which the door may be bodily retracted while still in its inclined position. In putting the door back in place, 30 reverse movements are employed.

The specific object of my invention is to provide simple and effective mechanism for opening and closing the door by the movements just described.

45 The various features of novelty which characterize my invention are pointed out with particularity in the claims annexed to and forming part of this specification: For a better understanding of the invention, 50 however, and the advantages possessed by it, reference should be had to the accompanying drawings and descriptive matter in which I have illustrated preferred embodiments of my invention.

55 Of the drawings;

Figure 1 is an elevation of my improved door handling mechanism and shows in section a portion of the coke oven structure with which it is associated;

Fig. 2 is a plan view of a portion of the 60 apparatus shown in Fig. 1;

Fig. 3 is an elevation taken similarly to Fig. 1 but on a larger scale, showing a portion only of the apparatus of Fig. 1;

Fig. 4 is a plan view of a portion of the 65 apparatus shown in Fig. 3;

Fig. 5 is a partial section on the line 5—5 of Fig. 3;

Fig. 6 is an elevation of a modified form 70 of mechanism;

Fig. 7 is a partial section on the line 7—7 of Fig. 8;

Fig. 8 is an elevation taken at right angles 75 to Fig. 6 with parts broken away and in section; and

Fig. 9 is a view taken similarly to Fig. 8 showing parts in different positions.

In Figs. 1-5 of the drawings, I have illustrated the use of my improvement in an installation in which the door handling mechanism for the "pusher" side of a horizontal by-product coke oven plant is mounted on the pusher machine carriage R. The latter also supports the coke ejecting ram T, the charge leveling bar U, and the mechanisms 80 for giving the ram T and the bar U their movements, and for giving the carriage R its movement transverse to the oven chambers along the pusher track rails S. The door handling mechanism proper comprises 85 a bar or beam A, mounted as shown on guide rolls A¹⁰ for movement toward and away from the oven chambers in a direction parallel to the longitudinal axes of the latter. This longitudinal movement of the bar 90 A is brought about through mechanism which as shown comprises a motor mounted on the carriage R, and operatively connected to the bar A by speed reducing gearing including a spur gearing W' in mesh 100 with a toothed rack secured to or formed on the bar A. The coke oven structure shown, comprises horizontal coking chambers P' with flued heating walls at each side of the chamber, and a door O for the pusher 105 end of each chamber which comprises a metallic rim or framework and a refractory body portion O'. In the closed position of the door shown in Fig. 1, the refractory inner body portion O' of the door projects 110

into the corresponding oven chamber P' , preferably to the outer edges of the first vertical flues P^2 in the heating walls. The side flanges of the door then abut against 5 the sides of the doorway. In the particular construction shown in Fig. 4 the sides of the doorway proper comprise metallic flash plates Q which cover the ends of the heating walls and are held in place by the usual 10 vertical buckstays Q' . At the top of the doorway the flash plates Q are shown as connected by a metal lintel Q^2 . The door is normally secured in its closed position by means of a horizontal locking bar O^4 15 which is vertically movable in the guideways O^5 carried by the door. The ends of this bar O^4 engage the inner inclined sides of the lugs or brackets Q^3 carried by the adjacent buckstays.

20 In so far as above specifically described, the oven structure and apparatus disclosed is of a known type.

The improved door handling mechanism shown in Figs. 1-5, comprises as its most 25 essential characteristic, a lever element E , which is pivotally connected to the sliding bar element A , to turn with respect to the latter about a horizontal axis parallel to and adjacent the lower edge of the door.

30 Associated with this lever are means for securing the door to the lever, and for turning the lever about the axis of its hinge connection to the bar A to thereby tilt the door from the normal closed position shown in 35 Fig. 1 into the inclined position shown in Fig. 2, or vice versa. The lever E may be directly hinged to the sliding element A , but for safety and convenience in operation, I prefer to interpose a yielding or 40 cushion connection between the lever E and the element A . Such a safety connection protects the apparatus in particular, from injury in case of an undue advance movement of the beam A . This safety connection, in the form shown, comprises an element B which straddles the beam A and is connected to the latter by links C and CA . A cushion spring D , interposed between the elements A and B normally holds the latter 45 in the advanced position shown in the drawing in which the yoke portion of the element B rests upon the top of the beam A . The legs of element B support at their lower ends a shaft B' by which the lever E is 50 hinged to the element B . Advantageously the link C is made about twice as long as the link CA and the two links are so arranged that when the bar A is moved too close to the door and the cushion spring D 55 yields to permit a backward movement of the member B relative to the member A , this relative movement will not create an appreciable change in the level of pintle B' .

The upper end of the lever E is bifurcated 60 to receive a door engaging hook lever G

which is pivotally connected to the lever E by a shaft E^2 . The lever E is turned relatively to the member B on the axis of the pintle B' by an electric motor F^4 on the member B , and a crank shaft F operated by 70 the motor and carrying crank pins F' which are connected by links E' to the ends of the shaft E^2 . The shaft of the motor F^4 is connected to the crank shaft F by speed reducing gearing, including spur gears F^2 75 inclosed in a casing F^5 (not shown in Fig. 3), and speed reducing gearing inclosed in a housing F^3 .

The door engaging lever G is provided at its inner end with a door engaging hook 80 adapted to take under a bracket or hook plate O^2 secured to the metallic frame of the door, preferably at a level appreciably above the center of gravity of the door. The outer end of the hook lever G is connected to an operating mechanism which comprises, in the preferred construction illustrated, a nut H screwed on a threaded spindle I and provided with trunnions H' , to which the two branches of the bifurcated 85 outer end of the lever G are pivotally connected. The lower end of the shaft I is journaled in a bracket K and the latter, in turn, is hinge connected to ear portions E^3 of the lever E by co-axial pins or shafts K' 90 which are parallel to the shafts E^2 and B' . Secured to the lower end of the shaft I is a bevel gear I' which meshes with a bevel gear J^2 , secured to a shaft J . The latter is journaled in the yoke K and provided at 95 its ends with hand-wheels J' . A suitable thrust bearing I^2 , which may advantageously be a ball bearing, is interposed between the upper end of the gear I' and the tubular portion of the yoke K in which the lower end of the shaft I is journaled. H^2 and H^3 represent tubular guards secured to the nut H and inclosing the threaded upper end of the shaft I . By rotating the hand-wheel J' , the nut H is raised and lowered 100 and the hook end of the lever G thus moved out of and into operative engagement with the hook plate O^2 . Advantageously, I associate with the lever G means for automatically moving the door locking bar O^4 into 105 and out of operative relation with the lugs Q^3 as the lever G is moved out of and into operative relation with the hook plate. The means for this purpose comprises a rock shaft L journaled in the lever E and having an arm connected by a link L' to the lever G and having other arms L^2 for engaging and lifting the bar O^4 .

To avoid undesirable relative movement 115 of the door O and lever E when the door is supported by the lever E through the hook G and to assist in properly closing the door, I provide the lever E with a door engaging part adjacent the lower end of the lever, and advantageously, though not necessarily, 120

130 to receive a door engaging hook lever G

made of a yielding character. As shown, this part is in the form of a plunger M mounted in a casing M' secured to the lever E adjacent its lower end. The outer end of a 5 plunger M engages the inner end of a cushion spring M² received in the casing M', and the outer end of the spring is engaged by an adjustable abutment member M³ projecting into, and adjustably secured in the 10 outer end of the casing M'.

The operation of opening the door O with the apparatus shown in Figs. 1-5, is as follows: The carriage R is adjusted on the track rails S to bring the bar A in front of the door to be opened. The bar A which has been previously retracted with respect to the carriage R to provide the necessary clearance between the door handling mechanism and buckstays Q' as the carriage is being moved along the rails S, is then advanced into the door engaging position shown in the drawings. This brings the hook end of the lever G under the hook plate O² and the arms L² under the locking bar 20 O⁴. The adjustment of the element A with reference to the carriage R need only secure approximate registration between the engaging surfaces of the lever G and hook plate O² since accurate registration may be 25 quickly and easily secured by a slight operation of the motor F and a corresponding angular adjustment of the lever E. To prevent an undue inward movement of the lever G, the latter is preferably formed with a 30 curved shoulder G² which abuts against the outer face of the hook plate O². After the lever E is thus brought into the proper relative position with respect to the door, the shaft J is rotated to bring the locking lever 35 40 into snug engagement with the underside of the locking plate O². The motor F⁴ is then operated to swing the lever E from the position occupied by it in Fig. 1 into position occupied by it in Fig. 2. This turns the 45 door from the position shown by it in full lines in Fig. 1, and in dotted lines in Fig. 3, into the full line position of Fig. 3. The 50 effect of this tilting of the door is to lift the bottom of the door off the door sill, and to 55 transfer the weight of the door from the door sill to the lever E and the mechanism for supporting the latter. After the door is turned into the position shown in full lines in Fig. 3, it may be fully withdrawn 60 from the oven chamber by the retraction of the beam A, and in practice provision may well be made for retracting the beam A far enough to carry the door to the outer edge of the oven bench P³. Then in normal operation, the carriage R is shifted as required to bring the ram T and the leveling bar U successively into alignment with the oven chamber.

To put the door back into place, after the 65 carriage R is returned to the position in

which the beam A is in line with the oven chamber, the beam A is advanced until the lower end of the door snugly engages the doorway, and the beam A should be advanced for this purpose far enough to put 70 the spring M², and spring D, if both are employed, under some tension. After this is done, the motor F⁴ is operated to swing the lever A toward the oven and thereby force the upper end of the door into the 75 closed position. After the door is thus brought up against the doorway, the shaft J is rotated to lower the hook lever G and the arms L², thus disconnecting the lever G from the door, and permitting the locking bar O⁴ 80 to lock the door in place.

The apparatus disclosed, in addition to possessing obvious advantages of simplicity in construction and operation, possesses a special advantage in that the warping of 85 parts resulting from the unequal expansion of different portions of the oven structure and tending to set the different doors when in their closed positions out of plumb in varying degrees, do not interfere with the 90 operation of the apparatus since such variations may be compensated for by a corresponding change in the angular adjustment of the lever E about the axis of its hinged connection B' to the member A. When, as 95 will be the ordinary practice, the axis of the shaft B' is slightly above the bottom edge of the door, the turning movement of the door from the dotted line to the full line position of Fig. 3 would tend to throw the lower 100 end of the door inward a slight distance if the door engaging part M were then rigidly connected to the beam A, but the yielding connection actually employed makes this tendency of no importance. To prevent any 105 possibility of the bar A being retracted while the hook lever G engages the door and before the lever E is tilted away from the position shown in Fig. 1, the operation of the motor W may be made dependent upon the position 110 of the lever E in such fashion that the latter cannot be operated except when the lever E is tilted into or near the position shown in Fig. 3. This may be accomplished by the use of such known means as are commonly employed for making the operation of one part 115 dependent on the position of another part.

It will be understood that the mechanism for turning the hook lever G about its fulcrum need not, and in practice should not, 120 be of a character to permit the door to be lifted off the door sill in this manner. All that is required of this mechanism is to bring the hook lever G snugly against the plate O² and to lift the locking bar O⁴. If 125 the door were lifted by the adjustment of the hook lever G any appreciable distance, the door might not clear the top Q² of the door frame when the lever E was subsequently turned to tilt the door.

In Figs. 6, 7, 8 and 9 I have illustrated a modified form of door handling mechanism especially adapted for use on the "coke side," though capable of use at either side of the 5 battery. As shown, this form of my invention is mounted on the coke guide carriage W⁹ having the chute or passage W¹⁰ through which the coke pushed out of an oven passes beyond the coke bench P⁸. The carriage W¹⁰ may be moved along the track rails W² from one oven to another by a motor W³. The mechanism comprises a lever member EA, corresponding in function and generally in 10 its door engaging parts to the lever E of the mechanism first described. It is not convenient to mount on the coke guide carriage W, a supporting beam for the lever EA like the beam A first described. In the construction shown in Figs. 6-9, the part carrying 15 the lever EA and moving its fulcrum axis or pivot A²¹ toward and away from the oven structure is a link or swinging frame AA pivotally connected to the top of the carriage W by means of a shaft A²⁰. Preferably the latter is located at a level well 20 above the top of the oven doors OA. The link AA, in the form shown, consists of two similar spaced apart members connected together by the shafts A²⁰ and A²¹, and between which the lever EA is located. In removing a door, the lever EA is first oscillated to turn the door from the full to the dotted line positions of Fig. 9, thus transferring the weight of the door to the link 25 AA, and the latter is then swung away from the oven into the position shown in full lines in Fig. 8. To provide the necessary clearance between the bottom of the door and the bottom frame work of the carriage 30 W⁹ without undue cutting away of the latter, the turning movement of the lever EA about its pivot A²¹ may be initially greater than is required to lift the door off the floor of the oven, and may be continued after the 35 link AA starts to swing away from the oven structure. The lever EA and link AA may be given their respective movements in various ways, but I consider the means shown for producing these movements especially 40 desirable on account of its simplicity and effectiveness. This means comprises a crank shaft FA, having crank arms F¹⁰ connected by links F¹¹ to the link AA, and crank arms F¹² connected by links F¹³ to the shaft E² 45 of the lever EA. The crank shaft FA is oscillated by a motor F¹⁵ having its shaft connected to the crank shaft by speed reducing gearing including the gear segment F¹⁴ mounted on the shaft FA. The crank arms 50 F¹⁰ and F¹² are so angularly displaced from one another, and so proportioned and connected to the levers AA and EA, that while the lever EA is being moved between the 55 full and dotted line positions of Fig. 9, the 60 lower end of the link AA will remain sta-

tionary or practically so. Preferably, also, the arrangement is such that the lever EA will move back relative to the lever AA, into or near a vertical position as it reaches its position farthest away from the 65 oven.

The lever EA carries a door engaging hook lever G operated and operating in the same manner as the lever G of the construction first described, except that in the construction of Figs. 6-9 the hand wheel JA for rotating the screw I is directly secured to the lower end of the latter. The lever EA carries a spring cushioned door engaging part MA which may well be identical with 70 the part M described above when intended to engage the same kind of doors. As shown, however, the part MA carries a door engaging member M¹⁰ which is adapted to engage the flash plates QA, at the opposite 75 sides of the oven chamber, when the lever EA is in its door engaging and disengaging position. To accommodate irregularities in the flash plate setting, resulting from unequal oven expansion or other cause, the 80 member M¹⁰ is preferably connected to the part MA by a vertical pivot M¹¹. The use of the pivoted flash plate engaging member M¹⁰ is made desirable by the form of the door OA, shown in Fig. 7, which has no 85 side flanges engaging the flash plates and thus limiting the movement of the door into the oven. The members MA and M¹⁰ can be used in the mechanism of Figs. 1-5 with 90 equal advantage where that mechanism is 95 employed to operate doors of the kind shown in Fig. 7. The gear segment F¹⁴ may be rigidly secured to the shaft FA, but in the construction shown, the segment is journaled 100 on the shaft FA to provide a yielding connection between the motor F¹⁵ and the swinging frame AA analogous to that formed between the beam A and member B by the spring D in the construction first described. The door closing connection between 105 the gear segment F¹⁴ and the shaft FA is formed by a spring Z coiled about the shaft FA and having a central bight portion Z' engaging one edge of the segment F¹⁴, and end portions Z² which engage a bar Y the ends 110 of which are secured to the two lever arms F¹². The bar Y passes through a slot F¹⁷ in the gear segment F¹⁴ and the tension of the spring Z normally holds the bar against the 115 end of the slot F¹⁷ which moves away from 120 the bar Y when excessive movement of the segment F¹⁴ in the door closing direction causes the spring Z to yield. In the door opening movement the engagement of the bar Y with said slot end wall forms a 125 positive connection between the segment F¹⁴ and the shaft FA. Certain novel features of the construction shown in Figs. 1 to 5 hereof and not specifically claimed herein are disclosed and specifically claimed 130

in my prior application Serial No. 259185 filed October 22, 1918.

While in accordance with the provisions of the statutes, I have illustrated and described the best forms of my invention now known to me, it will be apparent to those skilled in the art that changes may be made in the form of the apparatus disclosed without departing from the spirit of my invention as set forth in the claims appended hereto, and that certain features of my invention may be used to advantage without the corresponding use of other features.

Having now described my invention, what I claim as new and desire to secure by Letters Patent, is:

1. The combination with a structure having a chamber and a vertical door for the chamber at one side of the structure, of a door handling mechanism comprising a member movable toward and away from said side of the structure and door engaging means mounted on said member and movable relative to the latter to tilt a door engaged by said means about a horizontal axis parallel to said side of the structure and adjacent the bottom edge of said door and thereby move the upper end of the door horizontally out of or into the doorway and transfer the weight of the door from the structure to the door engaging means or from the latter to the structure accordingly as the door is tilted in one direction or the other.

2. The combination with a structure having chambers and vertical doors for the chambers at one side of the structure, of a door operating mechanism comprising a member, a lever pivotally connected to said member to turn with respect thereto about a horizontal axis parallel to said side of the structure and adjacent the bottom level of said chambers, said member being adjustable to move the pivotal connection between the member and lever toward and away from said side of the structure, and door engaging means carried by said lever and thereby move the upper end of the door horizontally out of or into the doorway and transfer the weight of the door from the structure to the door engaging means or from the latter to the structure accordingly as the lever is tilted about said axis in one direction or the other.

3. A door handling machine comprising in combination a vertically disposed lever, a member to which said lever is pivotally connected adjacent its lower end to turn about a horizontal axis, a carriage supporting said member and on which the latter is movable to move said axis horizontally in a direction transverse to its length, and means for connecting a door to said lever to turn with the latter about said axis.

4. A door handling machine comprising

in combination a vertically disposed lever, a member to which said lever is pivotally connected adjacent its lower end to turn about a horizontal axis, a carriage supporting said member and on which the latter is movable to move said axis horizontally in a direction transverse to its length, and vertically adjustable means for connecting a door to said lever to turn with the latter about said axis.

5. A door handling machine comprising in combination a vertically disposed lever, a member to which said lever is pivotally connected adjacent its lower end to turn about a horizontal axis, a carriage supporting said member and on which the latter is movable to move said axis horizontally in a direction transverse to its length, a door engaging hook lever pivoted to the first mentioned lever and means mounted on the latter for adjusting the hook lever.

6. A door handling machine comprising in combination a vertically disposed lever, a member to which said lever is pivotally connected adjacent its lower end to turn about a horizontal axis, a carriage supporting said member and on which the latter is movable to move said axis horizontally in a direction transverse to its length, a door engaging hook lever pivoted to the first mentioned lever and a hand operated adjusting connection including a nut and screw between the levers.

7. A door handling machine comprising in combination a vertically disposed lever, a member to which said lever is pivotally connected adjacent its lower end to turn about a horizontal axis, a carriage supporting said member and on which the latter is movable to move said axis horizontally in a direction transverse to its length, upper door engaging means and a lower yielding door engaging abutment carried by said lever.

8. A door handling machine comprising in combination a vertically disposed lever, a member to which said lever is pivotally connected adjacent its lower end to turn about a horizontal axis, a carriage supporting said member and on which the latter is movable to move said axis horizontally in a direction transverse to its length, and means for connecting a door to said lever to turn with the latter about said axis, and mechanism including a crank connected to said lever, a second crank connected to said member, and a common actuator for the two cranks for adjusting said member and turning said lever by amounts the relative magnitudes of which vary with the positions of said cranks.

9. The combination with a structure having vertical doorways and plug doors for said doorways at one side of the structure, of a door operating mechanism comprising a member, a lever pivotally connected to said member to turn with respect thereto

about a horizontal axis parallel to said side of the structure and adjacent the bottom level of said doorways, said member being adjustable to move the pivotal connection between the member and lever horizontally toward and away from side of the structure, and door engaging means carried by said lever and including an abutment adapted to engage the structure at the opposite side of a doorway to limit the movement of a door thereinto.

10. The combination with a structure having vertical doorways and plug doors for said doorways at one side of the structure, 15 of a door operating mechanism comprising a member, a lever pivotally connected to said member to turn with respect thereto about a horizontal axis parallel to said side of the structure and adjacent the bottom 20 level of said doorways, said member being adjustable to move the pivotal connection between the member and lever horizontally toward and away from said side of the structure, and door engaging means carried 25 by said lever, and including an abutment pivoted to the lever to turn about a vertical axis and adapted to engage the structure at the opposite side of a doorway to limit the movement of a door thereinto.
- 30 11. A door machine comprising in combination a movable carriage, a link member pivotally connected to said carriage at an upper level to turn about an axis parallel to the direction of movement of the carriage, 35 a lever pivotally connected to said member at a lower level to turn with respect to the latter about an axis parallel to the first mentioned axis, and a door engaging means carried by said lever.
- 40 12. A door machine comprising in combination a movable carriage, a link member pivotally connected to said carriage at an upper level to turn about an axis parallel to

the direction of movement of the carriage, a lever pivotally connected at a lower level to 45 said member to turn with respect to the latter about an axis parallel to the first mentioned axis, door engaging means carried by said lever, and mechanism for oscillating said member and lever comprising cranks 50 oscillating about a common axis and angularly displaced from one another, a link connection between one of said cranks and said member, and a link connection between the other of said cranks and said lever. 55

13. A door machine comprising in combination a movable carriage a link member pivotally connected to said carriage at an upper level to turn about an axis parallel to the direction of movement of the carriage, a lever pivotally connected at a lower level to 60 said member to turn with respect to the latter about an axis parallel to the first mentioned axis, door engaging means carried by said lever, and mechanism for oscillating 65 said member and lever comprising a rock shaft, angularly displaced crank arms secured to said shaft and connected one to said member and one to said lever, a motor, and gearing including a yielding element between 70 said motor and rock shaft.

14. The combination with a structure having a vertical doorway at one side and a plug door normally entering and closing said doorway, of door handling mechanism 75 for engaging said door and moving it into and out of said doorway including a part projecting beyond the sides of the door and adapted to engage the side of the structure and thereby limit the door closing movement 80 of said mechanism.

Signed at New York, in the county of New York and State of New York, this 19th day of April, A. D. 1920.

JOHN E. HUBBELL.
